UNITED STATES PATENT OFFICE

105,276

DESIGN FOR A WALL SIDING

Andrew G. Hauck, Cincinnati, Ohio

Application March 11, 1937, Serial No. 68,123

Term of patent 14 years

To all whom it may concern:

Be it known that I, Andrew G. Hauck, a citizen of the United States, residing at Cincinnati, in the county of Hamilton and State of Ohio, have invented a new, original, and ornamental Design for a Wall Siding, in which the following is a specification, reference being had to the accompanying drawing forming a part thereof.

In the drawing:

The figure shows an elevational view of a wall siding showing my new design. The siding is composed of overlapping elements of normal thickness which when assembled present the design as shown.

I claim:

The ornamental design for a wall siding as shown and described.

ANDREW G. HAUCK.
